UNITED STATES PATENT OFFICE.

JAMES H. BOYE, OF CHICAGO, ILLINOIS, ASSIGNOR TO THE BOYE NEEDLE COMPANY, OF CHICAGO, ILLINOIS, A CORPORATION OF ILLINOIS.

CURTAIN-ROD.

1,214,995.

Specification of Letters Patent.

Patented Feb. 6, 1917.

Application filed October 21, 1915. Serial No. 57,128.

To all whom it may concern:

Be it known that I, JAMES H. BOYE, a citizen of the United States, residing at Chicago, in the county of Cook and State 5 of Illinois, have invented a new and useful Improvement in Curtain-Rods, of which the following is a specification.

This invention relates particularly to flexible curtain-rods, such as are commonly 10 employed for sash curtains.

Curtain-rods of the type here referred to comprise close-wound spring wire coils; and the primary object of my invention is to provide a simple and effective connection 15 between the close-wound spiral and a bracket which is adapted for connection with a window frame, or a sash, as desired.

The invention is illustrated in its preferred embodiment in the accompanying 20 drawing, in which—

Figure 1 represents a broken elevational view of a window frame equipped with a curtain-rod (shown brokenly) constructed in accordance with my invention; Fig. 2 a 25 sectional view of the window frame, showing the improved curtain-rod in plan; Fig. 3 an enlarged view, partly in section, illustrating the manner in which the attachment may be connected with the spiral rod; Fig. 30 4 a broken sectional view, showing the parts assembled; Fig. 5 a broken elevational view, showing the end portions of the jaws of the connecting member; and Fig. 6 a sectional view taken as indicated as line 6 on Fig. 4.

35 In the construction illustrated, A, indicates a window frame; and B, my improved curtain-rod applied thereto.

The device, B, comprises a close-wound wire coil 1; a pair of brackets 2, adapted 40 for connection with a window frame, or with a sash, as desired, and a pair of connecting members 3, joining the extremities of the coil 1 to the brackets 2.

The brackets 2 may be of any approved 45 design; as shown, each bracket comprises a base portion 2^a, and a curved arm 2^b, which is provided at its extremities with an eye 2^c. Each bracket may be formed from sheet metal by suitable stamping operations.

Each connecting member 3 preferably 50 comprises a pair of jaws 3^a united by an eye or spring-web 3^b. The device 3 has approximately the shape of a cotter-pin, 55 the arms tending to spring apart somewhat.

They are fitted with a sliding sleeve 3^c, which is capable of movement between the eye 3^b and a stop 3^d located near the extremities of the arms. The arms are provided with inturned extremities or flanges 60 3^e which are adapted to engage the grooves of the spiral. One of the jaws is slightly longer than the other and the bights 3^f are obliquely set, to conform to the spiral groove of the spring. One of the arms 3^a 65 is adapted to serve as a stop for the end of the coil spring.

In assembling the parts, one arm of the connecting member 3 is slipped through the eye 2^c of the bracket 2; the sleeve 3^c is then 70 slipped onto the arms 3^a till the sleeve strikes against the eye portion 3^b; the coil spring 1 is then inserted between the jaws till it encounters the stop 3^d; and the sleeve 3^c is then moved outwardly along the jaws 75 until the jaws firmly grip the coil. Care is taken to have the teeth or flanges 3^e engage the groove of the spiral; and when the sleeve 3^c is moved outwardly to the extremities of the jaws, the jaws are caused 80 to properly engage the coil springs, thus forming a secure connection.

It may be stated that the members 3 are 85 adjustably connected with the spiral flexible rod; and should the spiral become distended unduly, one of the ends may be snipped off, and the corresponding connecting member 3 may be reconnected with the spiral rod, thus making it of the desired 90 length.

In forming the brackets 2, the arm 2^b may be made concavo-convex in cross section, thus stiffening the arm and at the same time giving the bracket a neat appearance.

The foregoing detailed description has 95 been given for clearness of understanding only, and no unnecessary limitation should be understood therefrom, but the appended claims should be construed as broadly as permissible in view of the prior art. 100

What I regard as new and desire to secure by Letters Patent is:

1. In means of the character set forth, the combination of a coil-spring, and an attachment device in alinement therewith 105 and comprising arms embracing the end portion of the coil and having inturned extremities conforming to a groove of the coil, said arms being united at their outer ends by an eye, and a sleeve on said arms 110

serving to hold them in gripping relation with the coil.

2. A device of a character set forth comprising a coil spring, a bracket, and a connecting member comprising a pair of jaws and an eye engaging said bracket, said jaws embracing the end portion of the coil and equipped with a slide serving to hold the jaws in gripping relation with the end portion of the coil.

3. A device of the character set forth comprising a coil, a bracket, and a connecting member having an eye portion engaging the bracket and arms embracing an end portion of the coil, one of said arms having an inwardly projecting stop limiting the insertion of the coil, and a sleeve embracing said arms and holding the extremities in gripping engagement with the coil.

4. A device of the character set forth comprising a coil spring, a bracket, and a

connecting member comprising an eye engaging the bracket and arms having in-turned extremities shaped to conform to a groove of the coil, and a sleeve on said arms serving to hold the arms in gripping relation with the coil.

5. A device of the character set forth comprising a pair of brackets provided with eyes, a coil spring, and connecting members joining the extremities of the coil spring to said brackets, each connecting member comprising an eye engaging the eye of the corresponding bracket, and arms embracing the adjacent extremities of the coil, the arms of each connecting member carrying a sleeve serving to hold the arms in gripping engagement with the coil.

JAMES H. BOYE.
